UNITED STATES PATENT OFFICE.

ELI BARTH AND FRANKLIN BARTH, OF NEVADA, OHIO.

STRAW-STACKER.

No. 843,063.

Specification of Letters Patent.

Patented Feb. 5, 1907.

Application filed February 20, 1906. Serial No. 302,150

To all whom it may concern:

Be it known that we, ELI BARTH and FRANKLIN BARTH, citizens of the United States, residing at Nevada, in the county of Wyandot and State of Ohio, have invented a new and useful Improvement in a Straw-Stacker, of which the following is a specification.

Our invention relates generally to straw-stackers, and more particularly to an attachment for pneumatic stackers, the object being to prevent the straw from being blown away from the place it is intended to be deposited.

With this object in view our invention consists in providing the end of the pneumatic tube with an adjustable frame, so that the straw can be deposited on the stack at any place desired; and the invention consists also in providing the frame with a hinged end and side pieces which can be easily and quickly adjusted; and the invention also includes very simple adjusting means in connection with the tube, so that the frame can be adjusted in any position desired from the tube.

With these objects in view the invention consists of the novel features of construction, combination, and arrangement of parts hereinafter fully described, and pointed out in the claims.

In the drawings forming a part of this specification, Figure 1 is a side view of a pneumatic stacker, showing the attachment in place. Fig. 2 is a perspective view of the attachment, showing the spout detached. Fig. 3 is a transverse section through the frames, showing the end frame removed.

Referring to the drawings, A indicates a thresher provided with the usual delivery-tube B, mounted on the top, at one end having the ordinary adjusting means connected thereto. Bands C surround the tube B adjacent its outer end, provided with apertured lugs C', in which the parallel bars D' are slidably mounted. The bars are bent outwardly at D', forming side bars D³, connected by end bars D⁴ and forming a frame D, which is covered with wire-netting. A cross-bar E connects the side bars D³ and is provided with upwardly and outwardly extending curved bars E' adjacent its ends, surrounded by coil-springs E² and having threaded ends. Connecting the bar E to the outer end bar D⁴ is a bar F, which is also provided with a curved upwardly and outwardly extending bar F' adjacent its end surrounded by a coil-spring

F² and having a threaded end. Side frames G, covered with wire-netting, are pivoted to the side bars D³ by bending the upper ends of the side bars around the bars D³, as shown at 60 G'. Bars G² are carried by the side frame G and project up above the frame D in alignment with the cross-bar E and are each provided with a ring G³ at its end and an opening through which the curved bars E' are 65 adapted to work and be secured therein by nuts E³. Ropes H are connected to the rings G³ and pass over the pulleys E⁴, arranged on the cross-bars E, and have their ends connected to levers I, arranged on the spout 70 working on segmental racks I', so that the sides can be thrown at any angle desired. An oblong end frame J, covered by wire-netting, is pivotally connected to the outer end bar D⁴ by bending the ends of the sides 75 around the bar D⁴, as shown at J'. A bar J² is secured to the end frame and projects up above the frame D in alignment with the bar F and is provided with a ring J³ at its end and an opening through which the curved 80 bar F' extends and is secured therein by a nut F³. A rope K is connected to the ring J³ and to one of the levers I, arranged on the spout, so that the end can also be adjusted.

A plate L is provided with downwardly and 85 outwardly extending arms L', having tube-shaped ends L², through which the bars D' pass, and are adjustably mounted thereon by set-screws L³, passing through the walls of the ends L² and engaging the bars D'. An 90 eye L⁴ is secured to the plate L, to which the ends of the rope M are secured, said rope passing over a pulley N, arranged adjacent the end of the spout and around a windlass O, secured on the other end of the spout, so 95 that the frame can be adjusted any distance from the end of the spout desired.

Having thus fully described our invention, what we claim as new, and desire to secure by Letters Patent, is—

100

1. In a straw-stacker, the combination with a delivery-spout, of a frame carried by said spout, side frames hinged to said frame, an end frame hinged to said frame and means for adjusting the side and end frames, independently of each other, for the purpose described.

2. In a straw-stacker, the combination with a delivery-spout, provided with apertured lugs, of parallel bars mounted in said lugs provided with a frame at their outer ends, side frames and an end frame pivoted

105

110

to said frame, having upwardly-projecting members and means connected to said upwardly-projecting members, for operating said sides and end, for the purpose described.

- 5 3. In a straw-stacker, the combination with a delivery-spout, provided with apertured lugs, of parallel bars mounted in said lugs carrying a frame at their outer ends, spring-actuated sides and end frames pivoted to said frame, a plate adjustably mounted on said parallel bars, and means connected to said plate for adjusting said frame, for the purpose described.

4. In a straw-stacker, the combination with a delivery-spout, of a frame covered with wire-netting adjustably mounted on the outer end of said spout, spring-actuated sides and end frames covered with wire-netting pivoted to said frame, having upwardly-projecting members, pulleys arranged on said frame, ropes connected to said upwardly-projecting members passing over the said pulleys having their ends connected to levers mounted on said spout, a pulley arranged on the outer end of the spout and a windlass arranged on the other end having its ends connected to the frame, for the purpose described.

5. In a straw-stacker, the combination with a delivery-spout, of apertured lugs arranged on the outer end of said spout, bars

mounted in said lugs carrying a wire frame at their outer ends, spring-actuated sides and end frames hinged to said frame, apertured bars projecting up from said side and end frames above the said frame, curved bars mounted on said frame projecting through the apertures in said bars ropes connected to said apertured lugs, and to levers carried by the spout, a plate provided with an eye adjustably mounted on the parallel bars, and a rope connected to said eyes passing over a pulley arranged on the end of the spout and a windlass arranged on the other end of the spout, for the purpose described.

6. In a straw-stacker, the combination with the delivery-spout, of bars slidably mounted thereon carrying a frame at their outer ends, spring-actuated side frames hinged to said frame, a spring-actuated end piece hinged to said frame, ropes connected to said side and end pieces, a plate adjustably mounted on said bars, and means for adjusting said frame and independent means connected to said ropes for adjusting the side and end frames, for the purpose described.

ELI BARTH.
